UNITED STATES PATENT OFFICE.

FREDERICK BENNETT, OF RAVENSWOOD, NEW YORK, ASSIGNOR TO WALKER & BENNETT MANUFACTURING COMPANY, OF NEW YORK, N. Y., A CORPORATION OF NEW YORK.

CAR-SEAT.

1,078,767.

Specification of Letters Patent. Patented Nov. 18, 1913.

Application filed June 18, 1909, Serial No. 502,904. Renewed April 7, 1913. Serial No. 759,572.

To all whom it may concern:

Be it known that I, FREDERICK BENNETT, of Ravenswood, Long Island, New York, and whose post-office address is 517 West 5 Twenty-ninth street, borough of Manhattan, city and State of New York, have invented certain new and useful Improvements in Car-Seats, of which the following is a full, clear, and exact specification, such 10 as will enable others skilled in the art to which it appertains to make and use the same.

My invention relates particularly to improved devices for mounting and shifting the 15 foot rest of a car seat simultaneously with the shifting of the back and cushion thereof, and it has for its object to provide mechanism for this purpose which will be positive and certain in its operation and 20 entirely free from rattling and uncertain action and by which the foot rest will be securely locked in both of its extreme positions, making it possible to shift the foot rest or seat by pressure against the former. 25 I attain this and other objects by certain novel features of construction and combinations of parts which will be fully set forth hereinafter and particularly pointed out in the claims.

30 Reference is now had to the accompanying drawings which illustrate as an example the preferred manner in which the principle of my invention may be embodied.

In these drawings—Figure 1 is an inner 35 side elevation of the mechanism at one end of the seat, the view omitting the cushion and back. Fig. 2 is an enlarged section on the line 2—2 of Fig. 1. Fig. 3 is a sectional elevation on the line 3—3 of Fig. 2, 40 and Figs. 4 and 5 are views illustrating the cam surfaces of the inner section of the actuator.

While my invention relates primarily to the devices for mounting and shifting the 45 foot rest and is applicable to any car seat, it is especially designed for use in connection with the cushion and back actuating devices forming the subject of my co-pending application Serial #454,599, filed September 24, 1908, and in Fig. 1 it is shown in connection with such devices. In said view 10 indicates one of the two frames for pedestals at the sides of the cushion. To each of these pedestals is fastened a horizontal guide bar 11. 12 indicates one of

the arms of the back pivoted to an arm 14 fastened on and swinging around the center of a horizontal shaft 15. 16 indicates a link, one end of which has a pin 17 working in a vertical guide 18 on the bar 11 and 80 having at its lower end a pin 19 working in a guide 20 in the lower end of the arm 12. By these devices the arms of the back and hence the back itself is mounted and held securely in either adjustment and 85 allowed to swing freely from one position to another, all of which is fully set forth in the co-pending application referred to.

The shaft 15, to which the swinging arm 14 is attached, has an enlargement 21 adjacent to the arm. This enlargement may be formed in any desired manner; it is here shown as a sleeve keyed to the shaft. Loose on shaft 15, and abutting against the enlargement 21, is a tubular shaft 22, which 70 carries rigidly at its inner end (the right-hand in Fig. 2) the outwardly projecting arm 23 of the foot rest 24. Outward of said tubular shaft 22 the end of the shaft 15 carries a collar 25 keyed to the shaft. 80

The actuator 26 is here shown in the form of a sleeve which loosely embraces the enlargement 21 of the shaft 15 and the sleeve 22, and which is adapted to slide on these parts, but is prevented from rotating by 85 means of ledges 27 at the sides of the actuator which bear on track bars 28 fastened to a projection extending inwardly from the pedestal 10 and braced at their inner ends by a yoke 29 which passes under the tubular 90 shaft 22.

As shown best in Fig. 4, the actuator 26 is constructed of two sections keyed to each other. This is a matter of convenience only and if this construction is followed the inner section 26^a is provided with a spiral groove 30, in which is received a pin 31 projecting from the enlargement 21 of the shaft 15. The actuator 26^a is also provided with a spiral groove 32, the ends of which run into straight or longitudinally disposed portions 32^a; and in this groove 32 is loosely received a pin 33 fastened to the tubular shaft 22. By this arrangement upon the rocking of the shaft 15 and its enlargement 100 21, due to the swinging of the arm 14, the pin 31 will act upon the side walls of the groove 30, and since the actuator 26 is incapable of rotation, it will be forced to move 105 longitudinally on the shafts 15 and 22. This 110

longitudinal motion of the actuator 26 causes the walls of the groove 32 to act on the pin 33 and impart a partial rotation to the shaft 22, owing to the fact that this shaft is incapable of axial motion by reason of the collar 25. This partial rotation of the shaft 22 brings about a swinging motion of the foot rest, and in this manner the foot rest is shifted.

- 10 The organized operation of the mechanism may be traced, as follows: Upon shifting the back of the seat from one position to another it is necessary to shift the foot rest but in a reverse direction. Consequently, 15 as the back is thrown over, its motion brings about a swinging of the arm 14 and a rocking of the shaft 15 but in a direction reverse to that in which it is necessary to swing the foot rest. This rocking of the shaft 15 brings about the before-described sliding motion of the actuator, and owing to the reverse disposition of the cam grooves 30 and 32 the shaft 22, arm 23 and its attached foot rest are caused to move reversely. 20 Therefore, as the back is thrown in one direction the foot rest is caused to move oppositely to shifted position. As the actuator reaches the ends of its motion the straight portions 32^a of the groove 32 engage the pin 33 and form a positive lock for the foot rest, so that a person pressing against the same will be unable to change its position.

It will be seen therefore that by means of 35 my invention a positive connection is established between the back and the foot rest and that the foot rest is shifted with a positive motion reversely to the motion of the back. It will also be seen that the actuator 40 and the parts concerned therewith involve a certain amount of friction which prevents idle motion of the parts and hence eliminates any rattling or loss of motion. It also eliminates any liability of the back to play 45 idly from one position to another.

Having thus described my invention, what I claim as new and desire to secure by Letters Patent of the United States, is:

1. In a shiftable car-seat, the combination 50 with a seat mechanism a part of which moves in one direction, of an adjustable foot rest a part of which is juxtaposed to said part of the seat mechanism and adapted to move reversely and an actuator acting 55 between said parts and movable longitudinally of the seat to drive the latter reversely to the former.

2. In a shiftable car-seat, the combination with a seat mechanism, a link connected 60 thereto and having a stationary axis about which it may swing, a foot rest having a part movable about said axis as a center and an actuator concentric with said axis for moving said foot rest reversely to said 65 seat mechanism.

3. In a shiftable car-seat, the combination with a seat mechanism, a link connected thereto and having a stationary axis about which it may swing, a foot rest having a part movable about said axis as a center 70 and a cammed sleeve concentric with said axis for moving said foot rest reversely to said seat mechanism.

4. In a shiftable car-seat, the combination with a seat mechanism, a link connected 75 thereto and having a stationary axis about which it may swing, a foot rest having a part movable about said axis as a center and a cammed sleeve movable longitudinally of said axis concentric with said axis for 80 moving said foot rest reversely to said seat mechanism.

5. In a shiftable car seat, the combination with the seat mechanism, a part of which moves in one direction, of an adjustable foot rest a part of which is juxtaposed to said part of the seat mechanism and adapted to move reversely thereto and an actuator sliding past said two parts and driving the latter reversely to the former. 85

6. In a shiftable car seat, the combination with the seat mechanism a part of which moves in one direction, of an adjustable foot rest a part of which is juxtaposed to said part of the seat mechanism and adapted to move reversely thereto, and an actuator having reversed cammed surface acting between the two parts to drive the latter reversely to the former. 90

7. In a shiftable car seat, the combination 100 with the seat mechanism a part of which moves in one direction, of an adjustable foot rest a part of which is juxtaposed to said part of the seat mechanism and adapted to move reversely thereto, and an actuator inclosing said parts and acting between them 105 to drive the latter reversely to the former.

8. In a shiftable car seat, the combination with the seat mechanism a part of which moves in one direction, of an adjustable foot rest a part of which is juxtaposed to said part of the seat mechanism and adapted to turn reversely thereto and an actuator inclosing the said parts and having reversed 110 cammed surfaces acting thereon to drive the latter reversely to the former. 115

9. In a shiftable car seat, the combination with the seat mechanism including a rocking shaft, a foot rest, a tubular shaft carrying the foot rest and inclosing a part of the 120 said rocking shaft, the rocking and tubular shafts having projecting portions and a reversely cammed actuator, the surfaces of which respectively engage the said parts of the shafts whereby upon motion of the 125 rocking shaft the tubular shaft is turned reversely.

10. In a shiftable car seat, the combination with the seat mechanism including a rocking shaft, of a foot rest, a tubular shaft 130

connected thereto and inclosing part of the rocking shaft, said shafts having projecting parts, an actuator inclosing the two shafts and having reverse cammed surfaces respectively engaging the projections of the shafts and means for preventing rotation of the actuator, whereby upon movement of the rocking shaft the tubular shaft is turned reversely.

In testimony whereof I have signed my name to this specification in the presence of two subscribing witnesses.

FREDERICK BENNETT.
